UNITED STATES PATENT OFFICE.

HENRY A. GUSTIN, OF CAMBRIDGE, MASSACHUSETTS.

DESIGN FOR A BICYCLE-CRANK.

SPECIFICATION forming part of Design No. 29,143, dated August 2, 1898.

Application filed August 19, 1897. Serial No. 648,832. Term of patent 3½ years.

To all whom it may concern:

Be it known that I, HENRY A. GUSTIN, a citizen of the United States, residing at Cambridge, in the county of Middlesex and State 5 of Massachusetts, have invented and produced a new and original Design for Bicycle-Crank, of which the following is a specification, reference being had to the accompanying drawings, showing a part thereof.

Figure 1 is a side elevation of the crank. Fig. 2 is an edge view.

The leading feature consists in a bicycle-crank the pedal end of which is bent at a right angle to the body portion at a point near its end. 15

What I claim is—

The design for a bicycle-crank, substantially as shown and described.

H. A. GUSTIN.
